COMBINED MAGNETIC TAPE DRIVE UNITS AND CONTROL UNIT

Richard G. Clayton, Detroit, and Thomas C. Abrahamsen,
Birmingham, Mich., assignors to Burroughs Corpora-
tion, Detroit, Mich.

Filed June 19, 1972, Ser. No. 264,073

Term of patent 14 years

Int. Cl. D14—02

U.S. Cl. D26—5 C

FIG. I

FIG. 1 is a perspective view of combined magnetic tape drive units and control unit embodying our new design;

FIG. 2 is a front elevational view thereof;

FIG. 3 is a right end elevational view thereof; and

FIG. 4 is a top plan view thereof.

We claim:

The ornamental design for combined magnetic tape drive units and control unit, as shown.
